UNITED STATES PATENT OFFICE.

GEORGE W. BOLL AND PASCHAL E. WILHITE, OF MOUNT HOPE, KANSAS.

TANK-HEATER.

SPECIFICATION forming part of Letters Patent No. 645,451, dated March 13, 1900.

Application filed October 18, 1899. Serial No. 734,024. (No model.)

To all whom it may concern:

Be it known that we, GEORGE W. BOLL and PASCHAL E. WILHITE, citizens of the United States, residing at Mount Hope, in the county 5 of Sedgwick and State of Kansas, have invented certain new and useful Improvements in Tanks; and we do hereby declare the following to be a full, clear, and exact description of the invention, such as will enable others skilled in the art to which it appertains to 10 make and use the same.

This invention relates to a new and useful improvement in watering-tanks for use by live stock; and its object, among other things, 15 is to provide a tank of simple and durable construction with means to prevent freezing of the contents of the tank during cold weather.

To these ends the invention consists in constructing the tank with, preferably, a cone-shaped bottom and a flue extending upward therefrom through the center of the tank to a point above the upper edge thereof; also, in providing means whereby the side of the 25 tank may be strengthened to resist any pressure which might be brought to bear thereagainst by the stock while drinking, &c.

The invention also consists in the further novel constructions and combinations of parts 30 hereinafter more fully described and claimed, and illustrated in the accompanying drawings, showing the preferred form of our invention, and in which—

Figure 1 is a perspective view of our improved tank with cover removed. Fig. 2 is a 35 central vertical section through the tank and its cover.

Referring to said figures by letters of reference, A is the side of the tank, which is 40 formed of any suitable material, as galvanized iron, steel, &c., and B is the bottom thereof, preferably cone-shaped, as shown, and secured to the side by means of rivets or in any other desired manner. A flue C extends upward from the center of the bottom, 45 with which it communicates, to a point above the upper edge of the side A and is provided with a suitable damper, as D, whereby the draft therethrough may be regulated as desired.

Within the chamber E, formed by the cone-shaped bottom B, is located a suitable device, as F, whereby the tank may be conveniently and expeditiously heated. This heating de-

vice may consist of a small furnace constructed 55 of boiler-iron or masonry, or, if desired, a lamp of suitable size may be placed within the chamber.

By means of the damper D the heat within the chamber E can be regulated, and by providing a cone-shaped bottom B the maximum amount of surface is exposed to the heat, which is also capable of reaching all points upon the bottom of the tank.

To the upper edge of the side A of the tank 60 is riveted an angle-iron, as G, which serves to brace the side against any pressure which might be exerted thereagainst by the stock.

If desired, a cover, as H, may be provided for the tank. This can be utilized for retaining 65 the heat within the water when the tank is not in use.

While we have described our tank as adapted 70 for watering stock, it is to be understood that the same may also be utilized for soaking corn or for cooking feed, if so desired.

The furnace F, which we have illustrated 75 in the drawings, is preferably semicircular in cross-section, as shown, and is provided with a chimney F', which extends into the flue C, 80 as shown.

In the foregoing description we have shown 85 the preferred form of our invention; but we do not limit ourselves thereto, as we are aware that modifications may be made therein without departing from the spirit or sacrificing the advantages thereof, and we therefore reserve the right to make such changes as fairly fall within the scope of our invention.

Having thus fully described our invention, 90 what we claim, and desire to secure by Letters Patent, is—

In a watering-tank, the combination, with the side, having strengthening means at its upper edge, of a conical bottom forming a 95 chamber thereunder, a furnace within said chamber, a flue extending from the bottom to a point above the upper edge of the side, a chimney to the furnace projecting into the flue, a damper in said flue, and a cover, substantially as described.

In testimony whereof we affix our signatures in presence of two witnesses.

GEORGE W. BOLL.
PASCHAL E. WILHITE.
